Patented Dec. 6, 1921.

UNITED STATES PATENT OFFICE.

HUBERT KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

DOUBLE SWITCH-BLADE.

1,399,492.

Specification of Letters Patent.

Patented Dec. 6, 1921.

Original application filed March 11, 1915, Serial No. 27,298. Divided and this application filed June 16, 1917. Serial No. 175,193.

To all whom it may concern:

Be it known that I, HUBERT KRANTZ, residing at Brooklyn, in the county of Kings and State of New York, have invented certain new and useful Improvements in a Double Switch-Blade, of which the following is a specification.

This invention relates to a double switch blade such as is shown and described in my pending application Serial No. 27,298 filed March 11, 1915, of which this is a division.

The object of this invention is to provide an improved switch blade and carrier therefor.

15 A further object is to provide an improved and efficient switch blade for use in controlling two independent circuits, that is, one which is adapted for swinging first between two given contacts for closing a circuit from 20 one of said contacts to the other, and then swinging from this position to break said circuit and further to close a circuit between two other given contacts.

25 A further object is to provide a switch blade as above which is of a flexible character and adapted, by its flexibility, to make an efficient electrical connection with all of said contacts.

Other objects and aims of the invention, 30 more or less specific than those referred to above, will be in part obvious and in part pointed out in the course of the following description of the elements, combinations, arrangements of parts and applications of 35 principles constituting the invention; and the scope of protection contemplated will be indicated in the appended claims.

In the accompanying drawings, which are to be taken as a part of this specification, 40 and in which I have shown merely a preferred form of embodiment of the invention:

Figure 1 is a longitudinal sectional view through a switch blade constructed in accordance with the provisions of this invention and showing the same supported in a suitable carrier, the section being taken substantially upon the plane of line I of Fig. 2.

Fig. 2 is a top plan view of the structure 50 shown in Fig. 1, and

Fig. 3 is a diagrammatic view illustrating a modification.

Referring to the drawings for describing in detail the structure which is illustrated 55 therein, the reference character L indicates

the carrier which is shown to comprise a pair of clamp plates 1 held together by rivets or bolts 2 and retaining the switch blade G between them. The carrier L is provided with a pivotal extension H by 60 means of which it may be pivotally supported to swing the switch blade ends into and out of contacting relation with the pair of stationary contacts 3 and 4 or into and out of contacting relation with the pair of 65 stationary contacts 5 and 6.

The plates 1 of the carrier engage the switch blade intermediate its ends so that the opposite end portions of the switch blade project a considerable distance beyond the 70 opposite edges of the carrier. The pivot H is preferably disposed so as to stand substantially midway between the ends of the blade and the contacts 3, 4, 5 and 6 are preferably equi-distant from said pivot so that 75 the switch blade may swing freely between them and in one of its positions will press against the parallel faces of the contacts 3 and 4 while in its other position it will press against the parallel faces of the contacts 5 80 and 6, as will be readily understood from an inspection of the drawings.

The switch blade illustrated is comprised of two sections as 7 and 8 held apart by a spacer 9 arranged between them and between the plates 1 of the carrier. The sections 7 and 8, and the spacer 9 are all of conductive material and are held in tight contact with each other by means of rivets 10 so as to comprise what may be referred 90 to as a main or body part and end contact parts projecting in spaced relation from the opposite ends of the body part. These parts may be insulated from the carrier in any suitable manner but are preferably insulated by a pair of insulating plates 11 arranged between the blade and the clamp plates 1 and by a pair of insulating sleeves 12 which surround the rivets 2. Other insulating plates 13 may be provided for closing the joint between the sleeves 12 and the insulating plates 11 in a manner which has been fully described and claimed in my co-pending application Serial No. 175,192, filed on even date herewith.

105 The sections 7 and 8 are substantially identical in all respects and each comprises a plurality of relatively thin strips 14 of conductive material, such as sheet metal, a pair of relatively heavy reinforcing strips 110

- 15 and 16 of like material arranged one outside of and one inside of the strips 14, and a third relatively heavy strip 17 of like material arranged inside of the strip 16. 5 The various strips 14 are each slightly longer from the outermost to the innermost strip and they are arranged so as to provide relatively beveled contact surface portions 18 at the opposite ends of the blade. 10 The strip 15 is somewhat shorter than the outermost strip 14 and is intended to prevent accidental bending or distortion of the strips 14 at any time either while handling or while in use. The strip 16 lies at all 15 times flat against the innermost strip 14 and also serves to prevent accidental bending or distortion of the strips 14. It also serves to stiffen the resilient action of the strips 14 in use. The strip 17 is somewhat 20 longer than any of the other strips and is provided with spark-heads 19 at its opposite ends beyond the toe of the beveled surfaces 18. These heads 19 normally lie in a plane beyond the beveled surfaces 18 so as 25 to be first to engage, and last to leave, the stationary contacts during the use of the blades, as will be readily understood.

The beveled surfaces 18 of the two sections 7 and 8 converge toward each other 30 and, when the switch blade is in the position of Fig. 1 the surface 18 at one end of one section engages the contact 3 while the surface 18 of the other section engages the contact 4. The presence of the spacer 9 35 and the rivets 10 enable the current to pass freely from one section into the other for completing the circuit between the contacts 3 and 4.

Of course when the switch blade is in its 40 opposite position, engaging the contacts 5 and 6, the two remaining bevel surfaces 18 of the sections will engage said contacts 5 and 6 and the current will pass in like manner.

45 All of the strips 14, 15, 16 and 17 are flexible and are adapted, when brought into engagement with the stationary contacts, to bend or flex. Inaccuracies of adjustment of the contacts, etc., are thus compensated for and a certain rubbing action against the contacts is provided so that a highly efficient electrical engagement results.

While the adjacent end portions of the 55 two sections of the blade are preferably intended to be independent from each other in their engagement with their respective contacts, nevertheless, in some instances, the two adjacent ends may coöperate if desired as shown in Fig. 1. Thus when the 60 spark-head 19 of one blade is pressed back by engagement with its stationary contact it may be pressed sufficiently far to in turn press against the adjacent spark-head of the other section. The resilient resistance offered by the other section will impart an

added force to the first spark-head pressing it more firmly against its stationary contact. The likelihood of the end of the first section being bent back too far is also avoided.

70 In the modification Fig. 3, the opposite end portions of the sections 7 and 8, are bent laterally away from each other so as to render said ends more completely independent in their actions. The bent end portions are spaced apart to provide air-spaces 75 20 between them and for improving the flexibility of the blade as has been fully set forth and claimed in my copending application above referred to.

75 As many changes could be made in this construction without departing from the scope of the invention as defined in the following claims, it is intended that all matter contained in the above description or 80 shown in the accompanying drawings, shall be interpreted as illustrative only and not in a limiting sense.

80 Having thus described my invention what I claim as new and desire to secure by Letters Patent is:

1. A switch blade comprising a body part, and a pair of contact parts having relatively movable laminations projecting from one side of the body part in the same general direction, the body part comprising means whereby the switch blade may be supported to swing the end portions of said contact parts from one stationary contact to another, and the end portions of said laminated contact parts each having a beveled end surface for engaging its respective stationary contact.

- direction, the body part comprising means whereby the switch blade may be supported to swing the end portions of said contact parts from one stationary contact to another, 5 and each of said contact parts comprising a plurality of strips of resilient material having their end edges arranged collectively to provide beveled contact surfaces for said contact parts, and the beveled contact surfaces 10 faces of the two contact parts being arranged in outwardly converging relation to each other for the purpose described.
5. A switch blade comprising a body part, and a pair of contact parts projecting from one side of the body part in the same general direction, the body part comprising means whereby the switch blade may be supported to swing the end portions of said contact parts from one stationary contact to another, 15 and each of said contact parts comprising a plurality of strips of resilient material having their end edges arranged collectively to provide beveled contact surfaces for said contact parts, a pair of spark-heads one for each 20 of said contact parts, and a pair of flexible members supporting said spark-heads in operative position beyond the toes of the bevels of the respective contact parts.
6. A switch blade comprising a body part, and a pair of contact parts projecting from one side of the body part in the same general direction, comprising means whereby the switch blade may be supported to swing the end portions of said contact parts from one stationary contact to another, and each 35 of said contact parts comprising a plurality of strips of resilient material having their end edges arranged collectively to provide beveled contact surfaces for said contact parts, and the beveled contact surfaces of the two contact parts being arranged in outwardly converging relation to each other for the purpose described, and a spark-head resiliently supported substantially at the 40 apex of the angle formed by said bevels.
7. A double ended switch blade comprising two sections of resilient material, a spacer between said sections intermediate their length retaining the intermediate portions of the sections spaced apart and leaving the end portions of the sections normally spaced apart but free to flex toward each other, the opposite ends of each section being oppositely beveled so that the bevels of 50 adjacent ends converge outwardly toward each other, and spark-heads resiliently supported substantially at the apexes of the angles formed by said bevels.
8. A double ended switch blade comprising two sections spaced apart, a spacer interposed between the intermediate portions 55
- of said sections to retain the intermediate portions spaced apart, each of said sections comprising a plurality of strips of resilient material projecting beyond the spacer to 65 provide flexible contact portions spaced apart at each side of the spacer, and the strips of each section being of varied lengths and being arranged to provide relatively beveled contact surfaces at the ends of each 70 section, said bevels being disposed oppositely to converge toward each other at the respective ends of the blade.
9. A switch blade comprising a body portion by means of which the blade may be 75 mounted, and a pair of spaced contact portions having relatively movable laminations projecting from the body portion in the same general direction, the laminations of each contact portion so terminating as to 80 form contact surfaces diverging from the tips of the contact portions toward the body portion.
10. A switch blade comprising a body part by means of which the blade may be 85 mounted, a pair of laminated contact parts having beveled edges and projecting from the body part in the same general direction, spacing means between said parts, and a spark head resiliently supported beyond the 90 outer end of one of said contact parts.
11. A switch blade comprising, a body part by means of which the blade may be mounted, a pair of laminated contact parts having beveled edges and projecting from 95 the body part in the same general direction, spacing means between said pair of parts, and a spark head supported beyond the outer ends of said two contact parts and in a plane therebetween.
12. A switch blade comprising a body part and two pairs of laminated contact extensions projecting from the body part, the body part comprising a spacer for spacing the two contact extensions of each pair from 100 each other, and said body part and extensions being all of conductive material and in current conveying contact with each other, whereby when either of the extensions of one of said pairs is engaged with a suitable circuit contact circuit will be 105 closed through said extension and through the body to either of the extensions of the other pair which may also be in engagement with another appropriate circuit contact.
- In testimony whereof I affix my signature 110 in the presence of two witnesses.
- HUBERT KRANTZ.
- Witnesses:
- J. L. KOLLE,
S. L. WHITLOCK.
